H. ERNST

DOOR GUARD

Filed Sept. 11, 1922

INVENTOR
HENRY ERNST

By Christopher Park Nelson

ATTYS.

UNITED STATES PATENT OFFICE.

HENRY ERNST, OF CHICAGO, ILLINOIS.

DOOR GUARD.

Application filed September 11, 1922. Serial No. 587,265.

To all whom it may concern:

Be it known that I, HENRY ERNST, a citizen of the United States, residing at Chicago, in the county of Cook and State 5 of Illinois, have invented a certain new and useful Door Guard, of which the following is a specification.

This invention relates to improvements in door guards of the type commonly used 10 in conjunction with ordinary door locks for burglar protection to prevent the door from being opened in the event the lock has been picked, broken, removed or otherwise rendered ineffective and adapted to permit of 15 a partial opening of the door as a precautionary measure, without unlocking the same to such an extent as to enable the entrance of an intruder.

The principal object of the invention is 20 to provide a door guard of the type referred to which is arranged to serve as a means whereby the door may be moved to and held securely in any one of a plurality of partially open positions for the purpose of providing ventilation for the room into which 25 the door leads.

A more specific object of the invention is to provide a door guard of the type employing a hinged strap with a bolt movable 30 in a slot in the strap, the strap having notches or sockets at intervals the length thereof into which a pin or other means provided for the purpose may be entered selectively to hold the door in a partially open 35 position to which it has been set.

Still another object is to provide a door guard which is adapted to serve in any one of three capacities; either to lock the door in a closed position, or to serve in conjunction 40 with the ordinary door lock and permit only a limited opening in the event the lock has been rendered ineffective, or to hold the door in any one of a plurality of partially open positions to which it has been set to afford ventilation to the room into which 45 the door leads.

The foregoing and other objects of the invention will appear in the following detailed description.

Referring to the drawing illustrating the invention, Figure 1 is a diagrammatic detail in section illustrating my improved door guard applied to a door between it and its casing, showing the door locked in a partially opened position at the extremity of the hinged strap. Fig. 2 is a detail looking

at the back of the casing on the door and showing the strap in section with the locking pin engaged therein. Fig. 3 is a transverse section of the casing taken on the line 3—3 60 of Fig. 2 looking in the direction indicated by the arrows. Fig. 4 is an elevational view looking at the back of a portion of the hinged strap, and Fig. 5 is a view similar to Fig. 2 but showing a modified form of 65 locking pin.

Throughout the views the same or similar numerals are applied to corresponding parts.

The device of the present invention is designed particularly for use in hotels or 70 other places where it is desired to set a door in a partially opened position to afford ventilation to a room without too greatly increasing the hazard of burglars. It is intended to be used principally where a transom or the like is not provided, or where such is provided but is of such a type that the hazard of burglars would be too greatly enhanced if the same were to be opened. In any event the device is adapted to serve so 75 as a door guard for burglar protection and is used in conjunction with the other ordinary lock provided for the door.

Devices of the type to which the present invention applies commonly comprise a 85 slotted strap 10 hinged to a plate 11. In the hinge connection I prefer to provide plain pins 12 which are held in place in a novel manner to be presently described. The plate 11 is fastened securely by screws 90 13 or in any other suitable manner, to the side of the door casing 14 in front of the jamb 15 and may be set in a recess provided therefor to afford clearance for the door 16. The plate 11 herein is shown as being 95 made of a piece of sheet metal bent over upon itself to provide pairs of spaced cylindrical ears 17 to receive the pins 12. The ears 17 have small lugs or barbs 17' thereon which, when the pins 12 have been assembled in the ears 17, are bent over as shown in Fig. 1 to hold the pins in place. A preferred manner of thus bending these lugs 17' is by means of the dies employed in the final shaping operation. In this operation the strap, having been completed, is assembled with the partially completed plate, with the pins 12 in position in the ears 17, the arrangement being such that as the dies are brought together the lugs 100 110 are forced downwardly over the ends of the pins. In this way the assembling op-

erations are obviously made more simple than where rivet pins are used. The plate 11 is preferably provided with struck-up lugs or bosses 18 to engage a shoulder at 19 in the side of the door casing to position the strap squarely with reference to the casing when it is being fastened. The strap 10 has a slot 20 extending longitudinally thereof thus bifurcating the strap to form parallel legs 10^a—10^a. The latter may be spread before the strap is assembled on the plate 11 so that when it is assembled a drag is placed on the swinging movement thereof by virtue of its frictional engagement with the ears 17 (see Fig. 4). A headed bolt 21 is arranged to move in the slot 20 and is rigidly mounted in the casing 22. The latter is fastened by screws 23 or the like to the door 16 at the edge thereof. The plate 11 may be cut away at 24 to admit the head of the bolt 21 when the door is closed. The strap 10 also is cut away on opposite sides of the slot 20 as at 25, to facilitate the entry of the bolt 21 into the slot with the head thereof on the outer side of the strap 10 when the door is opened, as, for example, by a burglar who has succeeded in rendering the lock on the door ineffective in some way. The door under such circumstances may be opened partially only to the extent permitted by the length of the slot 20 and in that event the opening is so small that a person could not possibly enter and is ordinarily so restricted that nothing could very well be projected into the room to fish articles therefrom.

A thumb piece such as that shown at 26 is commonly provided in connection with door guards of the type herein shown and is used for locking the door in a closed position. When the door is closed the strap 10 is swung over in front of it over the piece 26 which, when turned at right angles to the slot 20, serves to prevent the opening of the door. The edges 27 of the thumb piece 26 are preferably conformed to present a wedge face to the front of the casing 22 so that when the thumb piece is turned in the slot 20 the strap 10 is wedged in between the piece 26 and the front of the casing 22 and in this way is held quite securely.

Most of the foregoing features are common in door guards at present available and of course no invention is claimed therein, excepting only in so far as they cooperate as a part of the novel combination herein disclosed.

The strap 10 at intervals the length of the slot 20, is notched as shown at 28, four notches being illustrated provided on opposite sides of the slot 20. Adapted to cooperate with these notches is a pin 29 preferably of a generally U-shape, movably

mounted in the casing 22 (see Fig. 2) and having the bent portion 30 thereof projecting from the inner end of the casing to be gripped by the fingers for movement into and out of engagement with the notches 28. The free ends of the legs of the pin 29 are offset so that slight bumps 31 are produced near the bend 30 which serve to limit the extent of outward movement of the pin as it is withdrawn from engagement in the notches in the strap 10. Also withdrawal of the pin from the casing is prevented thereby. The offset ends of the legs of the pin 29 are first spread apart and then, in order to be entered through the openings 32 in the end walls of the casing 22, must be forced together in an obvious manner. The legs of the pin tending to spread after insertion into the casing produce considerable friction with the sides of the openings in the casing 22 as will be apparent. This friction serves to prevent the pin from being dislodged from engagement in the notches 28 in the event the door is attempted to be opened or moves slightly because of a draft.

It will appear that when the bolt 21 is projected into the slot 20 by opening the door partially, this is of course assuming that the strap 10 has beforehand been swung toward the door into operative position, the pin 29 may be moved out so that the two ends thereof are entered into any one of the sets of notches 28, as desired, to provide any desired degree of opening of the door within, of course, the limits afforded by the length of the slot 20. Thus in the present case there are four possible positions of opening to which the door may be set. The advantage of the arrangement is apparent. The door when set in any one of the positions of partial opening will not, because of a draft, move open any farther nor will it close because the pin as above described effectually holds the door in position and cannot readily be withdrawn by a person from the outside of the door. Or, even assuming that the pin has after considerable tampering been withdrawn, the door could still not be opened because the bolt 21 would perform its usual function. It is therefore apparent that the degree of burglar hazard is not enhanced very much when the door is thus set in a partially open position, and of course the hazard may be minimized even more by setting the pin at the first or second set of notches.

In Fig. 5 I have shown a modified form of locking pin at 29^a which is arranged so that only one end thereof may be engaged in notches in the strap 10. With this form it is of course necessary only to provide notches on one side of the slot 20 of the strap 10. This pin similarly to the pin

29 has a bent portion 30^a whereby it is manipulated and is offset at the end to form a hump 31^a to prevent its withdrawal from the casing. This pin likewise frictionally engages the casing after insertion and in that way is held in adjusted position.

The device is manifestly capable of modification in certain details thereof without departing materially from the general spirit of the invention. The appended claims are intended to cover all legitimate modifications and adaptations of the invention which would occur to one skilled in this art.

15 I claim as my invention:

1. The combination with a door and a casing, of a door guard comprising a slotted strap hinged to the casing for pivotal movement into and out of operative relation with respect to the door, a casing fixed to the door to move relative to said strap, a headed bolt carried by said casing with the headed end arranged to project toward said strap, said bolt being adapted to move in the slot in said strap with the shank thereof engaged in the slot, said strap having a notch formed intermediate the length of said slot on one side thereof and a pin carried by said casing slidable relative to said bolt alongside the shank thereof into said notch.

2. The combination with a door and a casing, of a door guard comprising a member fixed to said casing and having a slot extending lengthwise thereof, a member fixed to the door and having a head projecting therefrom arranged to operate in said slot to permit partial opening of the door, said slotted member having sockets formed intermediate the length of said slot on the sides thereof, and a pin adapted for movement selectively into any one of said sockets accordingly as it is desired to vary the degree to which the door is opened.

3. The combination with a door and a casing, of a door guard comprising an elongated member on said casing having a slot extending lengthwise thereof, a headed member on said door adapted in the movement of said door to operate in said slot, said slotted member having sockets formed intermediate the length of said slot on the sides thereof, and a pin movable selectively into any one of said sockets.

4. The combination with a door and a casing, of a door guard comprising an elongated member having a slot extending longitudinally thereof, a headed member adapted to operate in said slot, said slotted member having sockets formed intermediate the length of said slot on the sides thereof, a pin movable selectively into any one of said sockets, and means to cooperate with said pin to hold the same in operative position.

5. The combination with a swingable

closure, of means for selectively holding the same in any one of a number of positions of opening comprising an elongated slotted member, a casing movable relative thereto, a headed bolt in said casing movable in the slot in said member, said member having openings on the side of the slot therein, and a U-shaped pin slidable in said casing to engage an end thereof in one of said openings, one of the legs of said pin being bent to limit the degree of movement of the pin relative to the casing and to provide frictional engagement between said pin and said casing to hold the pin in its adjusted positions in said casing.

6. The combination with a swingable closure, of means for selectively holding the same in any one of a number of positions of opening comprising an elongated slotted member, a casing movable relative thereto, a headed bolt in said casing movable in the slot in said member, said member having openings on the side of the slot therein, and a U-shaped pin slidable in said casing to engage an end thereof in one of said openings, said pin having a leg thereof spread outwardly before insertion into said casing to spring against the side of the opening provided in said casing to receive the same when inserted therein whereby to provide frictional resistance to movement of said pin in said casing in operation, and a humped portion on said pin to prevent withdrawal of said pin from said casing.

7. In a door guard the combination of a plate arranged to be fastened to the door casing, and a strap hingedly connected to said plate and having a portion thereof arranged to serve as a limiting stop for the door to prevent more than a certain degree of opening of the door, said hinge connection comprising aligned apertured ears on said plate and strap, a pin entered in the apertures of said ears, and barbs in said ears at opposite ends of said pin arranged to be bent over to hold said pin in place.

8. The combination with a door and a door casing, of a door guard comprising a lever swingably mounted on the casing, said lever having a longitudinally extending slot terminating short of its outer end, and a plurality of spaced sockets opening into said slot, a bolt mounted on the door adapted to operate in said slot whereby only a limited opening of the door is permitted, a pin mounted on the door and slidable selectively into any one of said sockets, and means to cooperate with said pin to hold the same in operative position.

9. The combination with a door and a door casing, of a door guard comprising a lever swingably mounted on the casing, said lever having a longitudinally extending slot terminating short of its outer end, and a pair of oppositely positioned sockets open-

ing into said slot, a casing member fixedly mounted on the door relative to said lever, a headed bolt carried by said member adapted to operate in said slot whereby only 5 a limited opening of the door is permitted, and a U-shaped pin mounted in said member and slidably into said sockets to hold the door against movement.

10. The combination with a door and a door casing, of a door guard comprising a lever swingably mounted on the casing, said lever having a longitudinally extending slot terminating short of its outer end and a plurality of pairs of oppositely positioned 15 sockets opening into said slot, a casing member fixedly mounted on the door relative to said lever, a headed bolt carried by said member adapted to operate with its headed end in said slot, a U-shaped pin slidably 20 mounted in said member and projecting through openings in the end walls of said member with the legs of the pin in frictional engagement with the corresponding wall of the member, said pin being movable 25 selectively into any one of said pairs of

sockets to hold the door against movement.

11. The combination with a casing of a plate secured to said casing, and a strap hingedly connected to said plate, said hinge connection comprising alined apertured ears 30 on said plate and strap, a pin entered in the apertures of said ears, and barbs in said ears at opposite ends of said pin arranged to be bent over to hold said pin in place.

12. The combination with a door and door 35 casing, of a door guard comprising a lever swingably mounted on the casing, said lever having a longitudinally extending slot terminating short of its outer end, a bolt mounted on said door adapted to operate in 40 said slot whereby only a limited movement of the door is permitted, a pin mounted on said door and slidably into said slot to engage the latter in any one of a plurality of positions, and means to cooperate with said 45 pin to hold the same in operative position.

In testimony whereof, I have hereunto affixed my signature.

HENRY ERNST.
